UNITED STATES PATENT OFFICE.

CHARLES F. KETTERING, OF DAYTON, OHIO, ASSIGNOR TO THE DAYTON ENGINEERING LABORATORIES CO., A CORPORATION OF OHIO.

IGNITION DEVICE.

1,231,264.

Specification of Letters Patent. Patented June 26, 1917.

Application filed March 12, 1910. Serial No. 548,921.

To all whom it may concern:

Be it known that I, CHARLES F. KETTERING, residing at Dayton, county of Montgomery, State of Ohio, have invented certain new and useful Improvements in Ignition Devices, of which the following is a full, clear, and exact description.

The invention upon which the present application for Letters Patent is based, resides in a novel ignition system or combination of apparatus for internal combustion engines of automobiles and other vehicles, and comprises improvements in the elements of such a system and in their relations or manner in which they are associated or combined. The novel features consist chiefly in improvements in the dashboard switch or controller, the spark controlling device, a spark testing apparatus and the coil box, but as said improvements reside mainly in novel details of construction, contributing to the more effective operation of the system as a whole and the facility of its manipulation, they will be more easily described and more readily understood by the following detailed description in which reference is made to the accompanying diagram.

Certain parts of the invention embodied in the present case have been also clearly shown and described and claimed in my co-pending application, filed Nov. 14, 1910, Serial No. 592,290, which was filed as a division of the present case.

Figure 1 is a view, mainly diagrammatic, of the circuit connections and operative relations of the principal parts of the system.

Fig. 2 is a front and Fig. 3 a rear plan view of the dash-board switch mechanism, the outer casing being, in each view, removed.

Fig. 4 is a central longitudinal section of the switch box.

Fig. 5 is a cross-section of the same.

Fig. 6 is a plan view of a detached part of the mechanism in the same.

Fig. 7 is a side elevation of the apparatus contained in the spark controller box.

Fig. 8 is a top plan view of the same.

Fig. 9 is a top plan view of the plate carrying the spark testing keys.

Fig. 10 is a longitudinal section of the same.

Fig. 11 is a plan view of the under side of the same.

55

Fig. 12 is an end view of the spark controller with the casing therefor removed.

The ignition apparatus as a whole, and as diagrammatically illustrated in Fig. 1, comprises a galvanic battery and a magneto machine, as alternative sources of electric energy for the production of sparks. It has also the usual timer, a spark plug for each cylinder of the engine and a spark coil for each of said plugs, with appropriate circuit connections. In order that but a single spark shall be produced each time that the proper circuit connections are established by the timer, a special spark controller is used which is common to all of the spark plug circuits, and in order that either the battery or magneto may be brought into operation, there is employed a special switch, designed to be conveniently placed on the dashboard and provided with special devices, for controlling the operations of the apparatus, which will be hereinafter described in detail. A special spark tester is also employed which, with other details above mentioned, will be described by reference to the drawings.

The spark controller or circuit-breaker is contained in a box or casing 3, divided into two compartments by a partition 5, to which the two inclosing cases 4, 6 are secured in any convenient manner, as by rods 7 and nuts 8. The compartment formed by the case 4, is utilized for the circuit connections intermediate of the binding posts 9, and the several operative parts of the controller.

90

In the other compartment 6 is an electro-magnet 1, secured by its core 10 to the partition or head 5, and a condenser 2 similarly supported by a central rod 11. The magnet 1 has a double winding of fine and coarse wire respectively, so connected with the circuit as to impart like poles to the core. This is shown in Fig. 1, where 12 represents the coarse and 13 the fine coil.

The core of the said magnet is extended parallel to the coil forming a horse-shoe or U-core; the forward end of the said extension 14, having a right angled armature 15 pivotally mounted thereon.

The armature 15 is of the right angle type, one end of which is positioned in aline-

ment with the end of the magnet core 10, while the other end of said armature lies directly adjacent to an extended portion of the leaf spring contact plate 20.

5 The contact plate 20 coöperates with the leaf spring contact 21, each of these contact springs carrying at their free ends, platinum points 22 normally held in contact by means of a spring 23, pressing upon the contact plate 20, at a point substantially over the end 19, of the armature 15. Therefore, any wear which takes place between the platinum points of said contact plates, will be compensated for by the action of this 15 leaf spring 23.

The degree of movement of the armature, relative to the magnet core 10, may be suitably adjusted by means of the threaded core insert or pole piece 16, carrying a 20 notched disk 17, which is normally held in the desired position, by means of the spring catch 18.

The opposite end 19, of the armature is provided with a button 24, which in its 25 normal position, lies adjacent to, but entirely out of engagement with the contact plate 20, so that a certain limited play or lost motion is permitted the armature, previous to its engagement with the contact 30 plate 20, during its operation. Thus, if the armature should be drawn toward the core, by the residual magnetism thereof, no appreciable lifting pressure will be exerted upon the said contact by the armature.

35 Again, by arranging the armature 15, normally out of engagement with the contact plate 20, any wear of the contact points 22, will not affect the rate of vibration of the armature, inasmuch as the armature 15 40 will not be affected in any way by said wear. That is, if the button 24, of the armature 15 was normally in contact with the plate 20 and any wear occurred at the contact points 22, the spring 23 which is provided to take 45 up said wear, in order to maintain a good contact at the points 22, would also tend to force the end of the armature 15, which lies adjacent to the magnet core, away from the said core and thus increase the distance 50 therebetween. This would, of course, cause a variable rate of vibration of the armature, inasmuch as the space between the armature 15 and the pole piece would be duly increased in accordance with the amount of 55 wear which had taken place between the contact points 22.

In order that a certain definite resistance 60 may be offered to the movement of the armature 15, when brought in contact with the under face of the plate 20, the spring 23 is arranged to impinge the upper face of the plate 20, at a point substantially in alignment with the point at which the armature engages the under face of said plate.

The effect of this is to prevent the armature 65 from having a vibration period of its own, and thus render it capable of a "forced" vibration only.

In order to prevent injury to the contacts when the casing is removed or replaced, a 70 U-shaped bar 30 is mounted on a relatively stationary part of the circuit-breaker, for example the core extension 14 adjacent to the point of impingement of the contacts 20, 21, to afford protection to such parts during 75 removal and replacement of the casing.

The spark testing device to which reference has been made, comprises a series of push buttons or testing-keys 31 set in a plate 32 that may be mounted on the dash-board at a convenient point. The stems 34 of the said buttons extend through openings in an insulating plate or block 33, and through holes of less diameter in a metal plate 37, and a second insulating plate 38 80 85 beneath it. Contact terminal plates 35 are secured to the under side of the plate 38 over the holes through which the said stems work, and spiral springs 36 contained in the opening in plate 33, and bearing separately 90 against the plate 37, and collars on the stems 34, provide spring seats for the push buttons and complete the circuit between each of the same and the plate 37.

Plate 37 is connected to the wire common 95 to all the primaries, and plates 35, respectively to the outer terminals, so that by depressing a push button into contact with the plate 35 under it one of the primaries is short circuited and no spark produced in the cylinder corresponding thereto. By successively depressing the buttons while the engine is running the operation of the several spark plugs and cylinders may be observed.

The dash-board or controller switch shown 100 in Figs. 2 and 6 is operated to effect several operations desirable for the proper running of an automobile. Mechanically considered the device consists of a casing 39 within 105 which a projecting switch arm 40 is pivoted at 41, and which is capable of being set in any one of three positions, in one of which it brings into operation the battery as the 110 source of energy for the sparks; in another, the magneto, and in a third or neutral position, cuts both out of operation.

The base 42 is removable from the casing 39, but normally secured thereon by screws 43, and there is also pivoted at 44 a plate 45, connected to the base 42 by a spiral spring 46 located above its pivotal point 44.

The upper end of the switch arm or lever 40 is widened into a segmental plate, and the lower end of plate 45 has two projections 47 and 48 at its corners, the former rounded, the latter squared, to fit into corresponding notches in the edge of the segmental extension of lever 40.

When lever 40 is in its middle position, the projection 47 engages with its notch and retains the switch in such position with sufficient force to prevent accidental displacement, and at such time a projection 49 on the plate 45 rests against a limiting stop 50 on the base 42.

If the lever 40 be turned from such position in either direction the projection 47 riding over the rounded edges of the coöperating notch forces the upper end of plate 45 away from its stop 50 against the tension of the spring 46, tending to throw the switch and aiding to retain it in either of its extreme positions.

On one side of the base 42 is secured a pair of contact spring blades 51, 52, insulated from each other except at their ends which are normally in contact. On the opposite side of the base is a similar pair of contacts 53, 54, which are normally out of contact. The segmental extension of the lever 40 carries pins 55^a, 56^a, on its rear face, which engage with the pairs of contacts respectively, when the switch is thrown to its extreme positions. By reference to Fig. 3 it will be seen that throwing the lever 40 to one side separates contacts 51 and 52, while throwing it to its opposite position brings together contacts 53 and 54.

On the side of the base 42 opposite to that carrying the plate 45, is mounted a pair of blade contact springs 55, 56, insulated from each other except at the ends which are normally in contact. A spring-seated push button 57 set in a socket in the casing 39 has a stem that projects through an opening 58 in the plate 45, and when depressed engages the end of spring blade 55, separating it from contact with blade 56.

The stem of the push button 57 carries a collar 59 beveled around its under edge, and when the switch lever 40 is in its middle or neutral position and plate 45 in its corresponding position, depressing the push button brings the beveled edge of the collar into engagement with a correspondingly beveled edge of the opening 58 in plate 45, and forces the latter sufficiently to one side to permit the collar to pass beneath the plate and be engaged thereby. Fig. 5 shows the push button latched by the plate 45 in its depressed position.

In the plate 45 there is also an opening 60 exposing a disk 61 eccentrically pivoted to the base 42. The disk carries a stem which serves as a guide for a key that may be inserted through a hole in the casing 39, for the purpose of turning the disk 61. When the switch 40 is in either of its extreme positions and the plate 45 in its position corresponding thereto, a movement by the disk 61 will have no effect as the plate 45 is latched against movement in either direction by rea-

son of its engagement with the lever 40. 65 When the lever 40 is in its middle position, however, the projection 48 lies immediately over its notch and by turning the key the plate 45 will be shifted to the position shown in Fig. 6, thereby locking the lever 40 against movement in either direction.

It will be observed that such a movement by plate 45, whether effected by the lever 40 or by a key (disengages the push button 57, should the latter be latched in depressed 75 position.

The purpose and function of the various elements described above, as included in or associated with the controlling switch mechanism will be more clearly understood, in 80 view of the following:

When it is desired to use the magneto as a source of current, the switch lever 40 is thrown into the extreme right hand position shown in Fig. 1. This operation of the 85 switch handle tends to separate the contact points 51 and 52, and thus permits the current to pass from the magneto directly through the main circuit into the primary 90 winding of the induction coil.

It will be understood that in the illustration shown herewith, the current normally passes from the magneto through the contact plates 51 and 52, via wires which are directly connected across the line of the 95 main circuit.

The magneto 68 with its circuits, including the single primary 69, is clearly shown in Fig. 1, merely to illustrate the manner in 100 which the magneto may be thrown into or out of operation.

What may be termed the main switch, that is, the switch which is controlled by the handle 40, is adapted to coöperate in certain respects with the push button or supplemental switch actuated by the button 57. 105

The switch which is controlled by the handle 40, is designed to be so shifted as to throw the system into what may be termed, a single spark circuit. The other switch which is controlled by the push button 57, is adapted to so effect the system upon operation, that the battery circuit will act as a buzzer or vibrating coil system, and will permit the generation of a continuous succession of sparks throughout the interval that the engine timer is in position to complete the primary circuit.

The push button 57 and its coöperating parts are so arranged that the buzzer device or vibrating coil system may be brought into use either temporarily or continuously. That is, when the lever 40 is in middle position, the pressing in of the push button 57 latches the same in depressed position, thus permanently cutting out the locking coil of fine wire 13, so that the system will act as a simple vibrating coil system, throughout the 125

time that the button 57 is maintained in depressed or latched position.

If, however, the lever 40 is shifted to the left or shifted into the position shown in Fig. 1, and designated "battery", whereby the system will normally produce a single spark for each time that the primary circuit is closed by the engine timer, then the pressing in of the push button 57 will only temporarily cut out the locking coil 13 and only cause the system to act as a vibrating coil system, for such time as the push button is held depressed by the operator. The reason for this is that the button 57 cannot be latched in depressed position at any time, other than when the lever 40 is in its intermediate or "off" position.

In the operation of motor vehicles, it is some times difficult to effect the starting of the engine with simply a single spark system, and it is a well known fact that it is equally difficult to effect the starting of a combustion or explosion engine, by means of magneto ignition. In view of this, the present invention may be used to especial advantage with motor vehicles, and when so used, will provide a source of ignition which will provide means whereby a series of hot sparks may be generated or produced in the proper cylinder of the engine, by means of a vibrating coil system. This type of ignition (vibrating coil) may be most advantageously used when starting, and when once started, the type of ignition may be instantly changed to either a single spark type of battery ignition or to magneto ignition.

From the above, it will be seen that the initial operation of the system, providing an engine to which the system is applied, is about to be started; is to throw the switch handle 40 into its neutral or "off" position and to then depress the push button 57. The depressing of the button 57 will, as has heretofore been stated, cause the beveled collar 59, carried by the shank of said button, to pass through the opening 58, formed in the plate 45. This plate 45 is resiliently mounted, and capable of limited lateral movement, and will be forced to one side, on the downward movement of the button 57, as has heretofore been described.

As soon as the collar 59 has passed through the opening 58, the plate 45 is drawn back into its normal position by means of the spring 46, and the beveled edge of the opening 58 will effectually engage the upper face of the collar 59, thus retaining the push button 57 in depressed position and consequently forcing the contact plate 55 away from plate 56, and thus breaking the normal contact therebetween, (see Figs. 1 and 5).

As has heretofore been stated, it may be desirable, in view of providing a safety de-

vice for preventing the use of the car by other than the rightful user, to positively lock the switch in inoperative position, and thus effectively cut off the source of ignition. In the present instance, this is accomplished by means of the eccentric disk 61, operating upon the plate 45, to shift and maintain the same in locked position, relative to the switch handle 40.

However, it will be obvious that the lever 40 might be in its neutral or "off" position and the push button 57 in depressed position, as has been described above, whereby the ignition system, in operation, would be of the vibrating coil type. To lock the switch in this position, would, of course, be to defeat the object sought.

It has been arranged, therefore, to automatically release the push button 57 from engagement with the plate 45, by the turning of the disk 61, and the consequent locking of the lever 40, in "off" position. This is clearly shown in Figs. 2 and 6, wherein it will be seen that if the disk 61 is moved into the position shown in Fig. 6, the plate 45 will be so actuated that the engagement between the edge of the opening 58, in the plate 45, and the collar 59, carried by the push button 57, will be broken and the pressure of the spring which normally maintains the push button 57 in outward position, will effectually return the push button to its normal position.

When the plate 45 is moved into position to lock the lever 40, it will also be in such position that the portion 58a of the plate 45, will prevent the push button 57 from again being depressed until at such time as the switch may be unlocked.

A short description of the circuits and electrical connections will now be given.

Supposing that the switch is thrown into "battery" position, (see Fig. 1) and that the push button 57 and the timer 65 are also in the position shown in Fig. 1, the current will pass from the battery 25, through the coarse wire winding 12, thence through the branch wire 110, contact plates 20 and 21, wire 102, wire 63, switch contact plates 53 and 54, wire 64, into the timer and thence through the primary winding 27, to the proper induction coil, back to the battery.

As soon as the current passes through the heavy winding 12, it energizes the magnet core 10 which in turn will attract the armature 15, and consequently break the contact between the plates 20 and 21, thus effecting a break in the main circuit.

In order to maintain the armature in attracted position until such time as the primary circuit is broken by the normal rotation of the timer 65, the current upon going from the battery, will flow through the heavy winding 12, and a small portion of

the current only, will also flow back through the fine wire winding or high resistance locking coil 13. From this coil, the current flows through the wire 66, through supplemental switch plates 56 and 55, main switch plates 53 and 54, wire 64, to the timer, thence back to the battery.

It should be understood that only sufficient current passes through the fine wire winding to sufficiently energize the magnet core to maintain the armature in attracted position and thus cause the continued separation of the contacts 20 and 21, as long as the main circuit is closed.

15 Supposing the switch is in neutral position and it is desired to employ the system as a vibrating coil system. It will be seen that the contact plates 53 and 54 will be out of contact and thus prevent the flow of 20 current through the main circuit. However, if the push button 57 (see Fig. 1) is held depressed so as to engage with the plate 55, a shunt circuit about the switch plates 53 and 54 will be formed through the 25 wire 67, plate 55, button 57 and branch wire 70.

It will, of course, be understood that the fine wire winding under these conditions, will be cut out and that the system, through 30 the operation of the armature 15, will be converted into a vibrating coil system.

It is to be understood that the construction herein specifically illustrated and described is merely the preferred embodiment 35 of the invention, which may be embodied in other forms without departure from its proper spirit and scope.

I claim:

1. In an electric ignition system for internal combustion engines, the combination 40 with a sparking circuit, a source of current therein, a spark timer, and an electromagnetic circuit-breaker capable of operation either to make single breaks in the circuit 45 under the control of the timer or to make successive breaks independently of the breaks in the timer, of a controlling switch to open and close the circuit at the will of the operator, manually actuated means for 50 determining the character of operation of the circuit-breaker, and means under the control of said switch for latching said manually actuated means in operative position.

2. In an electric ignition system for internal combustion engines, the combination 55 with a sparking circuit including a spark timer, of an electromagnetic circuit-breaker capable of operation either to make single breaks in the circuit under the control of 60 the timer or to make successive breaks independently of the breaks in the timer, a manual controlling switch in the circuit, having open and closed positions, manually actuated means for determining the charac-

ter of operation of said circuit-breaker, and 65 mechanism operable when the said switch is in its open position for latching said manually actuated means in operative position.

3. In an electric ignition system for internal combustion engines, the combination 70 with a circuit-breaker of the single and successive-break type, of a manual controlling switch in circuit with the circuit-breaker, manually actuated means for determining the character of operation of the circuit-breaker, and latching mechanism for said 75 means, releasable by the said controlling switch.

4. In an electric ignition system for internal combustion engines, in combination, a 80 circuit-controlling switch having open and closed positions, a manual circuit-controller operable in any position of the switch, and automatic mechanism operable in the open position of the switch to latch the said circuit-controller, and means for releasing said circuit-controller at will.

5. In an electric ignition system for internal combustion engines, in combination, 90 a circuit-controlling switch having open and closed position, separable normally closed contacts in circuit with the switch, a push-button adapted to separate said contacts, automatic latching mechanism for the push-button operable when the said switch is in 95 its open position, and means actuated by the switch to release the push button from said latching mechanism when the switch is thrown to a closed position.

6. In an electric ignition system for internal combustion engines, a circuit controlling 100 device comprising in combination, a switch lever, circuit contacts actuated thereby, a push-button, circuit contacts actuated thereby, automatic latching mechanism for the 105 push-button, and means actuated by the switch lever for disengaging the latching mechanism and the push-button.

7. In an electric ignition system for internal combustion engines, in combination, 110 a sparking circuit, a magneto and a battery in parallel in said circuit, an electromagnetic circuit-breaker in circuit with the battery and capable of operation either to make single breaks in the battery circuit or to make 115 successive breaks therein, a controlling switch having a neutral position, a position in which the sparking circuit is closed through the magneto, and a position in which the sparking circuit is closed through the battery, manually actuated means to determine the character of operation of the electromagnetic circuit breaker, and automatic latching mechanism for said means 120 operable when the controlling switch is in its neutral position.

8. In an ignition system for combustion engines, in combination, a plurality of pri-

mary circuits; a plurality of secondary circuits, inductively related to the respective primary circuits, and each provided with a spark gap; a source of current connected to 5 the primary circuits; and a plurality of testing keys, normally independent of the primary circuits, but operable to short-circuit any of said primary circuits at will.

9. In an electric ignition system for internal combustion engines, in combination, 10 a plurality of induction coils having primary and secondary circuits, said secondary circuits being provided with spark-gaps, and means, including a series of testing keys, 15 for short-circuiting any primary winding at will, said means normally being independent of the said circuits.

10. In an electric ignition system for internal combustion engines, the combination 20 with a circuit-breaker of the single and successive-break type, of a controlling switch in circuit with the circuit breaker and having open and closed positions, manually actuated means for determining the character 25 of operation of the circuit breaker, latching mechanism for said manual means, and a locking device operable to lock the switch in open position and concurrently operate said latching means to release said manual 30 means.

11. In an electric ignition system for internal combustion engines, the combination with a sparking means, comprising a battery 35 sparking circuit and a magneto sparking circuit; of a circuit controlling switch having three positions, viz., a battery position, a magneto and an intermediate off position; and a supplemental switch operable in any one of the three positions of said 40 controlling switch to coöperate with said sparking circuits to cause a succession of sparks therein.

12. In an electric ignition system for internal combustion engines, the combination 45 with a sparking means, comprising a battery sparking circuit and a magneto sparking circuit; of a circuit controlling switch having three positions, viz. a battery position, a magneto and an intermediate off position; 50 and a supplemental switch operable in any one of the three positions of said controlling switch to coöperate with said sparking circuits to cause a succession of sparks therein; with means for latching said supplemental switch in operative position upon its 55 operation, when the controlling switch is in its off position.

13. In an electric ignition system for internal combustion engines, the combination 60 with a sparking means, comprising a battery sparking circuit and a magneto sparking circuit; of a circuit controlling switch having three positions, viz., a battery position, a magneto and an intermediate off po-

sition; and a supplemental switch operable 65 in any one of the three positions of said controlling switch to coöperate with said sparking circuits to cause a succession of sparks therein; with means for latching said supplemental switch in operative position upon its operation, when the controlling switch is in its off position; and means connected with said controlling switch for automatically releasing said latching means in the supplemental switch when the controlling switch is moved either to its magneto 70 position or its battery position.

14. In an ignition system for internal combustion and explosion engines, the combination with a magneto system, and a battery system of the single and successive spark type of ignition; of a switch for selecting either the single spark or the magneto system of ignition; and a supplemental switch operable to place the successive 80 spark type of battery ignition in operation, independent of the position of the first named switch.

15. In an electric ignition system for internal combustion engines, the combination 90 with a circuit-breaker of the single and successive-break type, of a controlling switch in circuit with the circuit breaker and having open and closed positions, manually actuated means for determining the character 95 of operation of the circuit breaker, latching mechanism for said manual means, and a locking device operable to lock the switch in open position and concurrently operate said latching means to release said manual 100 means, with provisions connected with said manually actuated means for automatically preventing the re-operation of the same after it has been unlatched and released by the operation of said locking device to lock 105 the switch in open position.

16. In an electric ignition system for internal combustion engines, the combination with a circuit breaker of the single or successive spark-type; of a controlling switch 110 in circuit with the circuit breaker and having open and closed positions; manually actuated means for determining the character of operation of the circuit breaker; and a locking device operable to lock said switch 115 in open position and also lock said manually operated means in its inoperative position.

17. In an electric ignition system for internal combustion engines, the combination with a circuit-breaker of the single and successive-break type, of a controlling switch in circuit with the circuit breaker and having open and closed positions, manually actuated means for determining the character of operation of the circuit breaker, latching mechanism for said manual means, and a locking device operable to lock the switch in open 120 position and concurrently operate said 125

latching means to release said manual means; with provisions coöoperating with said locking device to prevent its operation to lock said switch when latter is in its 5 closed position.

18. In a system for supplying combustion and explosion engines with ignition, the combination with a plurality of ignition systems; of a switch element for selecting 10 certain of said ignition systems; and means independent of said switch element capable of operation to select a different type of ignition from the type of ignition selected by said switch element, independently 15 of the position of said switch element.

19. In a system for supplying combustion and explosion engines with ignition, the combination with a battery system of the 20 single and successive spark type of ignition; of a controlling element for the successive spark type of ignition; and a switch element movable to a position to select the single spark type of ignition and to an inoperative 25 position, independent of the position of the controlling element.

20. In an ignition system for combustion and explosion engines, the combination with a battery system of the single and successive 30 spark type of ignition; of a controlling element for the successive spark type of ignition; a switch element having a position to select the single spark type of ignition and an inoperative position in which 35 the said controlling element for the successive spark system is operable; means adapted to latch said controlling element in operable position, when it is actuated at the time the switch element is in its inoperative 40 position; and means actuated by said switch element when it is moved into position to select the single spark system, to release said controlling element.

21. In a system for supplying combustion and explosion engines with ignition, the 45 combination with a plurality of ignition systems; a switch element having operative and inoperative positions; a manually actuated element operable independently of said 50 switch element, for selecting one of the ig-

nition systems; means for latching said manually actuated element when operated while said switch element is in its inoperative position; and means operable by said switch element to release said manually actuated 55 element when the switch element is moved to its operative position; and locking means operable to lock said switch element in its inoperative position, said locking means being adapted to release the manually actuated element when it is in latched position, and to prevent the re-operation of the switch element.

22. In an ignition system for combustion and explosion engines, the combination with 60 a manually actuated element for controlling said system; of means operable to release said element from its operative position and having provisions to lock said element in its inoperative position.

23. In an ignition system for combustion and explosion engines, the combination with a sparking circuit; of a controlling switch having operative and inoperative positions; a manually actuated element for selecting 75 one type of ignition; latching means operable to maintain said manually actuated element in operative position, when the same is operated while the switch element is in one of its inoperative positions, said latching means having provisions whereby no engagement with said manually actuated element will be effected when the same is operated while the switch element is in operative position.

24. In an ignition system for combustion and explosion engines, the combination with a magneto and a battery system; a switch element for bringing said magneto system 80 into operation; and a supplemental switch operable to place said battery system in operation concurrently with or independently 85 of said magneto system.

In testimony whereof he affixes his signature in the presence of two subscribing witnesses.

CHARLES F. KETTERING.
